UNITED STATES PATENT OFFICE.

PAUL SIPTROTT, OF NEW YORK, N. Y., ASSIGNOR TO LEVOLITE CO. INC., OF NEW YORK, N. Y.

DESIGN FOR A WALL BRACKET.

Application filed February 15, 1926. Serial No. 16,525. Term of patent 3½ years.

To all whom it may concern:

Be it known that I, PAUL SIPTROTT, a citizen of Germany, residing in the city of New York, borough of Manhattan, in the county and State of New York, have invented a new, original, and ornamental Design for Wall Brackets, of which the following is a specification, reference being had to the accompanying drawing, forming a part thereof, in which—

Figure 1 is a view in elevation of the wall bracket, showing my new design; and

Figure 2 is a side view of the wall bracket shown in Figure 1.

I claim—

The ornamental design for a wall bracket, as shown.

PAUL SIPTROTT.
